ATTORNEY.

UNITED STATES PATENT OFFICE

JOHN M. OLSON AND LOUIS E. NELSON, OF FARGO, NORTH DAKOTA, ASSIGNEES TO CHAMBERLIN METAL WEATHER STRIP COMPANY, OF DETROIT, MICHIGAN, A CORPORATION OF MICHIGAN

METAL THRESHOLD

Application filed January 5, 1931. Serial No. 506,572.

This invention relates to metal thresholds, particularly such thresholds for exterior doors of a building, and the object of the invention is to provide a metal threshold having an exterior portion in insulated relation with an interior portion whereby heat or cold is not readily transmitted to the interior of the building by reason of the threshold element extending from the exterior to the interior of the building.

Particularly is the invention applicable for prevention of transmission of cold and accumulation of frost on the interior portion of a metal threshold.

15 The preferred form of construction of a metal threshold embodying these various features of the invention is shown in the accompanying drawing in which—

Fig. 1 is a transverse section showing my improved threshold in assembled relation with a door and sill, a portion only of which is shown.

Fig. 2 is a sectional view showing a part of the exterior portion of the threshold in perspective.

Fig. 3 is a similar perspective view in end section of the interior portion of the threshold.

The drawing Fig. 1, in so far as the threshold is concerned, is practically full size from which it will be observed that the threshold consists of two parts or sections 1 and 2, the exterior part 1 having a downwardly sloping outer portion terminating in a down curved 35 end 3 to contact with a sill 4.

The sill may be stone or other construction and the section 1 is secured in place by retaining screws 4 of which there may be several for which purpose the outwardly extending 40 flange like portion is provided with a series of countersunk apertures 5 one of which is indicated in Fig. 2. The section 1 has a horizontal part or step position 6 over which the lower end of the door 7 rides and this lower edge of the door 7 is provided with a bronze strip 8 having a downwardly inturned return-bent end 9 forming a channel to fit over the projecting edge of this horizontal portion 6 of the member 1 as the door is closed.

50 The door has attached thereto a spring bronze

sealing strip 10. These strips 9 and 10 form no part of the present invention as any type of sealing strip adapted for the purpose may be used with my improved threshold and the member 1 may be formed or constructed 55 for co-operation therewith to prevent ingress of air through the interstice between the bottom edge of the door and the threshold.

The feature of the invention resides in the provision of a threshold having the inner portion thereof within the interior of the building in an insulated relation with the portion 1 extending to the exterior of the building. By such an arrangement an accumulation of 60 frost is prevented on this section 2 which is the portion of the threshold exposed to view within the building. The purpose of my invention is to obviate such unsightly appearance and tendency to readily transmit cold to the interior.

70 The preferred arrangement of the two parts is shown in the drawing but various changes may be made in the form of the parts and the construction of the spaced insulated edges. The feature of the invention is involved in the use of two threshold parts connected together by inter-engaging portions spaced one from the other by an insulating material indicated at 11 in the construction shown. In this preferred form shown in Fig. 80 1, the inner edge of the part 1 has a foot portion 12 resting upon the floor 13 and/or sill 4 which is of channel like form extending longitudinally of the section 1. The upturned flange 14 forms a recess to receive the insulation 11 which may be of any approved 85 material for the purpose, such as a rubberized insulating felt or other known commercial product or any material that will serve the purpose. It will be noted that the inner member 2 has a downturned edge flange 15 lying in the channel formed by the foot portion 12 and upturned edge 14 thereof and that the insulation encloses this flange 15 preventing 90 transmission of heat or cold to a material degree to the interior of the building. The portion 2 is separately secured in position by means of screws 16 extending through apertures one of which is indicated at 17 in Fig. 3.

95 The threshold in other respects is similar 100

to known constructions in that the opposite ends thereof are usually embedded in the masonry at the opposite sides of the door opening or, in the event masonry construction is not utilized about the door, these ends may be correspondingly fitted to place with the door frame or wall defining the door opening of any of the usual constructions. The term "insulating material" as herein used is intended to mean any adaptable material of low heat conductive quality.

It is further to be noted that while we have shown a door in the drawing opening outwardly toward the exterior of the building, this threshold is equally adaptable for use with doors opening interiorly of the building in which case the sealing strips 9 and 10 will be placed on the opposite flange of the upper member 6 and the door simply reversed in respect to its relationship with the threshold as is herein shown.

It is to be understood that the invention is equally adaptable for use with hinged windows as well as for doors in which case the two parts 1 and 2, substantially of the same form as shown in Fig. 1, are mounted upon the sill of the window and the element 7 of Fig. 1 is indicative of the relationship of the swinging window or door as the case may be in either of which positions of installation the sealing strips 9 and 10 may be utilized in the same manner as here indicated. The words "metal threshold" as employed in the claims is intended to refer to the metal element having the insulation between the parts thereof whether utilized with a door or a hinged window.

From the foregoing description it is believed evident that the various objects of the invention are attained by the construction described.

What we claim and desire to secure by Letters Patent of the United States is—

1. A metal threshold for an exterior door of a building, consisting of two sections extending transversely of the door opening and both secured to the sill or floor portion therebelow, the section extending to the exterior of the door having a longitudinal channel open at its upper face adjacent the interior face of the door with the base of the channel providing the support for the inner edge of the exterior section and the other section having a depending flange lying in the said channel, and an insulating material positioned between the said depending edge and the channel walls.

2. A metal threshold for the exterior door of a building, consisting of two sections extending transversely of the door opening, one section having a portion thereof extending exteriorly of the door terminating in an upturned edge providing an open channel supported by the sill and further having a foot-like portion toward the opposite edge engag-

ing the sill and supporting the same, the other section being independently secured to the floor or sill interiorly of the door and having its outer longitudinal edge engaging in the channel of the first section in insulated relation with the inner longitudinal edge of the first member.

3. A metal threshold for the exterior door of a building having a door opening and a sill, consisting of two metal sections extending transversely of the door opening, the exterior section having a step portion and integral oppositely extending flanges therebelow one of which extends to the exterior of the door in spaced relation with the step portion and the other of which extends to a position slightly inwardly of the inner face of the door terminating with an open channel like portion at its inner edge resting upon the sill, and a second and separate inner section having an inner edge resting upon the floor and extending upwardly therefrom in curved form practically in alignment with the upper surface of the inwardly extending flange of the first section and having a down-turned edge engaging in the open channel, and insulating material in the channel separating the said inner and outer sections.

4. A metal threshold for an exterior door of a building having a door opening and a sill, comprising two metal sections extending transversely of the door opening, the exterior section having a step portion provided with a flange extending to the exterior of the opening and a flange extending and terminating approximately in the plane occupied by the inner face of the door when closed, said flanges providing an interior and exterior support for the step portion, a second section interengaging with the first section and extending inwardly from the interior flange of the first section, and insulating material between the said sections.

In testimony whereof we sign this specification.

JOHN M. OLSON.
